(57) **CLAIM**

The ornamental design for a light stand, as shown and described.

DESCRIPTION

FIG. 1 is a first perspective view of a light stand, showing my design.

FIG. 2 is a second perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a perspective view of the light stand showing the status when the light stand is unfolded.

FIG. 10 is a perspective view of the light stand showing the status when legs of the light stand are folded; and,

FIG. 11 is an enlarged view of a circle labeled 11 in FIG. 7 of the light stand.

The broken lines in the drawings illustrate portions of the light stand which form no part of the claimed design.
